CLAIM

The ornamental design for a display screen or portion thereof with animated graphical user interface, as shown and described.

DESCRIPTION

FIG. 1 is a front view of a display screen or portion thereof with animated graphical user interface showing the first image of a sequence showing my new design;

FIG. 2 is a second image thereof;

FIG. 3 is a third image thereof;

FIG. 4 is a front view of another embodiment of a display screen or portion thereof with animated graphical user interface showing the first image of another sequence showing my new design;

FIG. 5 is a second image thereof; and,

FIG. 6 is a third image thereof.

The broken lines around FIGS. 1-6 show a display screen or portion thereof that forms no part of the claimed design. The broken lines within FIGS. 2, 3, 5, and 6 show portions of the animated graphical user interface that form no part of the claimed design.

The appearance of the animated images sequentially transitions between the images shown in FIGS. 1-3 and 4-6. The process or period in which one image transitions to another forms no part of the claimed design.
